UNITED STATES PATENT OFFICE.

JOHN JOSEPH DEVITT AND JOHN CORCORAN, OF YONKERS, NEW YORK.

LOOM FOR WEAVING TUFTED FABRICS.

SPECIFICATION forming part of Letters Patent No. 367,094, dated July 26, 1887.

Application filed April 24, 1885. Serial No. 163,303. (No model.)

To all whom it may concern:

Be it known that we, JOHN JOSEPH DEVITT and JOHN CORCORAN, both of Yonkers, in the county of Westchester and State of New York, have invented a new and Improved Loom for Weaving Tufted Fabrics, of which the following is a clear, full, and exact description.

This invention relates to needle-looms designed more especially for weaving tufted fabrics—such, for example, as moquette carpets; and the invention consists of certain improvements in the construction and operation of the following-named parts—viz., the shuttle-race and carrier, the tension device for the west-thread, the nippers that draw the tuft-yarns down through the warp, the knives that cut the tufts, and the comb that lifts the tuft-yarns up through the warp.

Reference is to be had to the accompanying drawings, forming part of this specification, in which similar letters of reference indicate corresponding parts in all the figures.

Figure 1 is a sectional plan view of our new loom, taken on the line $x-x$, Fig. 2, parts being broken away to show the construction of other parts of the loom. Fig. 2 is a side elevation of the loom. Fig. 3 is a sectional elevation of the loom, taken on the line $y-y$ of Fig. 1, parts being broken away to avoid confusion. Fig. 4 is a sectional elevation taken on the line $z-z$ of Fig. 1. Figs. 5, 6, 7, and 8 are detailed views of the means for operating the tuft-cutting knives. Fig. 9 is a transverse sectional elevation of the knives and their supporting-plates, showing also one of the spring-retaining posts in elevation. Figs. 10, 11, 12, and 13 illustrate, respectively, in enlarged views and in connection with sections of carpet, the sequence of movements of the nippers, the lay, the comb, and the knives, Figs. 10 and 11 showing in sectional elevation tuft-yarn spools and their frames and a portion of the transfer-arms. Fig. 14 shows a section of the fabric and the knives ready to cut the tuft-yarn, and Fig. 15 shows an enlarged section of a part of the tufted fabric or carpet made by the loom. Fig. 16 is a side view of the cam E^5 , that moves the shuttle.

A represents the main frame of the loom,

which may be of any appropriate form and size to receive the power-shaft B and other working parts.

Upon the bracket A' of the main frame A is formed or secured the shuttle-race B' , and upon the arm A^2 , on the opposite side of the frame A, is placed the sliding block C, to which is attached the needle D, which is reciprocated by means acting upon the block C for carrying the filling or west thread a between the warp-threads b and across the loom to the shuttle E, that is properly reciprocated by means acting upon the shuttle-carrier E' and carries a thread, c , for forming with the west-threads a one selvage of the carpet or fabric being woven.

The shuttle-race B' is, by preference, curved, as shown in Fig. 1, and it is channeled or grooved in its upper surface, as shown at d , Figs. 1 and 4, to form the flanges d' to receive the T-rib d' , formed upon the under surface of the shuttle-carrier E' , which rib holds the carrier in place. A plate, E^2 , is secured to the inner edge of the race B' , against which the shuttle E runs, and this plate E^2 has the opening e , Fig. 4, made through it for the passage of the point of the needle D, and this plate E^2 has also the guard f secured to it to prevent the looping or tangling of the shuttle or selvage thread c , where it reaches from the completed portion of the fabric to the shuttle.

The shuttle-carrier E' has the studs gg formed upon its upper surface, and the carrier and the shuttle E are reciprocated upon the race B , so as to produce a reciprocating action, in which there is a dwell while the needle is withdrawn past the shuttle by the vertical shaft E^3 and the forked arm or plate E^4 , secured to its upper end, the shaft E^3 being rotary reciprocated by the cam E^5 on shaft B, and the spring E^6 , (shown clearly in Fig. 1,) the said cam E^5 acting to turn the shaft E^3 by the lever F and connecting-rod F', that connects the lever F with the horizontal arm F^2 , attached to the shaft E^3 . The arms or prongs $e' e'$ of the divided plate E^4 embrace the pins $g' g$ of the shuttle-carrier E' , and also the ends of the shuttle E, and as the shaft E^3 and plate E^4 are rotary reciprocated the prongs $e' e'$ cause the

shuttle and shuttle-carrier to traverse the curved shuttle-race B', and the prongs e' e' are such distance apart relative to the length of the shuttle and the distance the pins g' g are 5 apart as to leave space for a slight movement of the shuttle-carrier independent of the plate E', so that the shuttle will not cut or break the weft-thread a in passing through the loop or fold thereof formed by being carried across 10 the loom by the needle D. The needle D is reciprocated by the cam G on shaft B acting through the lever G', bell-crank lever G², and the connecting-links G³ and G⁴, which respectively connect the lever G' with lever G² and 15 the latter lever with the block C, as shown clearly in Fig. 4. The lever G' is held in contact with the cam G by the heavy coiled spring G⁵. (Shown in Fig. 2.) The needle D is formed with the hooks or prongs h, and made spoon-shaped at its inner end, as shown clearly in Fig. 1, so that as it carries the weft-thread forward 20 through the opening e in the plate E' in front of the shuttle E, the back of the needle will not interfere with the shuttle in picking up the loop or fold of the weft thread, which the nose or 25 point of the shuttle will hold while the needle D recedes. Then the shuttle will be carried on by the action of the cam E' through the loop or fold and back to the rear of the race 30 B', ready again to take up and pass through the next shot of weft-thread forced forward by the needle D. The weft-thread a comes from the spool H, placed at the needle side of the loom, and passes from the spool H first up 35 between the tension wheels i i', then through the eyes i' i' i'', and is fed to the needle D—that is, laid across the hooks h thereof from the front by the feeder J, which is pivoted at j and formed with the prongs or arms j' j'', that 40 straddle the weft-thread a, and is reciprocated by the action of a cam, J', on the shaft B and the spring J', that act through the lever J' and connecting-rod J''. (Shown clearly in Fig. 2.) The feeder straddles the weft-thread a at a 45 point slightly in front of the point of the needle when the same is withdrawn to the limit of its outward movement, as shown clearly in Fig. 1. The tension-wheel i is held in stationary bearings, while the wheel i' is 50 journaled at the lower end of the arm k, which is properly reciprocated for grasping and releasing the weft-thread by the cam K on the shaft B and the spring K', the cam and spring acting through the lever K² and the connecting-rod K'', that connects the lever K² with the arm k, as shown in Fig. 2. Any slack that 55 may occur in the weft-thread a will be taken up by the grooved roller k', which is of considerable weight and rests against the weft-thread, as shown in Figs. 1 and 2, the spring k² being provided to prevent the roller k' and pivoted arm k'', on which it is mounted, from dropping out of place when the loom is not in operation.

60 In weaving tufted fabrics the yarn l, (see sheet 3 of the drawings,) from which the tufts

are formed, will be carried on spools l', attached to spool-frames l'', carried upon endless chains L, that pass around the chain-shaft L', the same as in Letters Patent No. 233,290, dated October 12, 1880, and the spool-frames will be carried from the chain L down near to the warp-threads b by transfer-arms M, the same as in said patent.

For drawing the tuft-yarns l from the spools l' down through the warp-threads to be wrapped around the weft or filling and bound in or upon the fabric, we employ a series of nippers, N, (shown in Figs. 3, 10, and 11,) arranged so that a pair of nippers will stand between each pair of warp-threads. The nippers are composed of the jaws m and n. The jaws m are attached to the bar O, while the jaws n are attached to the bar O', that is secured to the bar O by the pins or bolts o, that 85 pass through the slots of in the bar O', the slots permitting the bar O' to have a slight longitudinal movement for opening and closing the jaws, this movement being imparted by the cam O² on the shaft B (see Fig. 1) acting through the lever O³, attached to the bar O', and pivoted or fulcrumed on the stud or pin o², formed upon the bar O, as shown in Fig. 3. The bar O is attached by the arms o³ and o⁴ to the shaft p, the arm o³ being pivoted 90 to the arm o⁴, which is rigidly secured to the said shaft p. The bar O is also attached by the connecting-rod p' to the arm p² of the sleeve p³, that is placed loosely upon the shaft p. The shaft p has the downwardly-projecting arm p⁴ attached to it, and the sleeve p³ has the downwardly-projecting arm p⁵ attached to it, so that the said shaft p and sleeve p³ may be rotary reciprocated by the cams P' P² (shown 95 in Fig. 1) on shaft B, acting through the levers p⁶ p⁷ and connecting-rods p⁸ and p⁹. This movement of the shaft p and sleeve p³ serves to raise the nippers to the position shown in Figs. 3 and 10, where they are closed to grasp the tuft-yarns and to lower and advance them to the position shown in Fig. 11, where they stand out of the way of the lay Q and reed R. (Shown clearly in Fig. 3.) Before reaching the position shown in Fig. 11, the nippers, after drawing the tuft-yarns below the warp, are 105 opened by the action of the cam O² and lever O³ to release the tuft-yarns l, leaving the ends thereof between and reaching below the warp-threads, as shown in Figs. 11 and 12. The tuft-yarns being thus drawn down through the 110 warp and released by the nippers, the needle D puts in a shot, b', of weft or filling, which of course stands in front of the tuft-yarns l, as shown in Figs. 11 and 12, and then the weft is beaten up by the lay Q, which is operated by 115 the cam Q' on shaft B, acting through lever Q², connecting-rod Q³, and arm Q⁴ of the lay, the same being secured upon the shaft Q⁵, as shown clearly in Fig. 3. The beating having been 120 performed, the comb R, the teeth q of which are upturned, as shown clearly in Fig. 12, is 125 operated by mechanism, hereinafter described,

so as to comb up or raise the lower ends of the tuft-yarns l around the shot b' —that is, raise them from the position shown in Figs. 11 and 12 to that shown in Figs. 13 and 14. This 5 done, and while the comb R still holds the yarns l , the needle D inserts the shot of filling b^2 , which is beaten up and bound by the warp, and then the knives $S S'$ are brought forward from the position shown in Figs. 1, 2, and 3 10 to that shown in Fig. 14.

The knives $S S'$ have a shear-cut, each being formed with corresponding cutting-fingers, $s s$, (shown clearly in Figs. 5 and 9,) the sharp edges of which are moved across each other at 15 the proper time by a longitudinal movement of the knives $S S'$. The knives $S S'$ are held upon the horizontal cross plate T , attached to the arms $T' T'$, rigidly secured to the above-mentioned shaft P , held in the frame of the 20 loom between the center screws, $t t$. The knives are kept in position upon the plate T by the bolts or studs $t' t'$, that pass through slots in the knives, so that the knives may be moved longitudinally in opposite directions. 25 The lower knife, S , has the eye-stud t^2 secured to it, which reaches up through the slot t^3 in the upper knife, S' , and this upper knife has the eye-stud t^4 secured to it, and to these eye-studs $t^2 t^4$ are attached the ends of the coiled 30 spring U , that normally holds the knives in such position that the cutting-fingers of the upper knife stand immediately over the cutting-fingers of the lower knife, as shown in Fig. 5, so that when the knives are carried 35 rearward for cutting the tufts the tuft-yarns will come properly between the cutting-fingers. The knives are carried rearward to cutting position by the action of the cam V on shaft B acting through the lever V' , (shown clearly 40 in Figs. 6 and 7,) the connecting-rod V^2 , and arm V^3 , the latter being rigidly secured to the shaft P , as shown clearly in Fig. 6. The knives are brought back to vertical position by the 45 spring V^4 . (Shown in Fig. 6.) The knives having been carried down to the tuft-yarns in cutting position, they are moved longitudinally to cause the cutting-fingers s to effect the cutting of the yarns by the cam W acting through the levers $W' W'$ and chains $W^2 W^3$, that connect the knives $S S'$, respectively, with the 50 outer ends of the levers $W' W'$, as shown in Fig. 5. The said chains pass over the pulleys $w w$, so that when the adjacent ends of the levers $W' W'$ are elevated by the toe on the 55 cam W the corresponding depression of the outer ends of the lever will draw downward upon the chains, and thus simultaneously move the knives longitudinally in opposite directions. The toe of the cam W having passed 60 the levers $W' W'$, the spring U will act to return the knives, and also the chains and the levers W' , to their original positions. The cam W is secured upon the shaft W^5 , which is 65 revolved from the main shaft B by the beveled gear-wheels W^6 . (Shown clearly in Figs. 1 and 8.)

The comb R is pivoted at its ends to the bars $R' R'$, that are held in the race-pieces R^2 R^3 , and are reciprocated longitudinally from the cams $R^6 R^8$ on shaft B by the bent levers R^4 70 (see Fig. 3) and springs R^5 , that draw the levers R^4 backward, as illustrated in the last-mentioned figure. The comb R while being moved forward is tilted by the cams R^6 acting through the levers R^7 and connecting-rods R^8 , 75 so that the teeth of the comb pass down through the warp threads b just in the rear of the tuft-yarns l . Then, by the action of the cams R^6 , levers R^7 , and rods R^8 , the comb is tilted back to bring the upturned ends of the 80 teeth q in front of and in line with the yarns l , as shown in Fig. 12. Then the springs R^5 , in connection with cams R^6 and levers and rods $R^4 R^8$, act to gradually draw backward the comb R , the teeth of which are at the same 85 time tilted upward by the cams R^6 and levers R^7 and rods R^8 , which movements continue until the comb reaches the position shown in Fig. 13, where it completes the work of combing the yarns l around the shot b' of weft or filling, 90 which is inserted by the needle D , as above described. At the position shown in Fig. 13 the comb R dwells while the slot b^2 of filling is inserted by the needle D , after which it is carried back to its original position—that 95 shown clearly in Figs. 1 and 3—ready to repeat the operation for each row of tufts that is put in the fabric.

In Fig. 2 L^2 represents the selvage-point, which is pivoted above the warp b , and is reciprocated by a cam, L^3 , on the shaft B , through the lever l^6 and connecting-rods l^7 , (shown in Figs. 1 and 2,) so that it drops over each slot of weft or filling thread a just after each stroke of the lay Q , to hold the filling at the selvage 100 while the next shot is being inserted by the needle D , thus making a close weave at the edge of the fabric, as will be understood clearly from Fig. 2.

Having thus described our invention, what 110 we claim as new, and desire to secure by Letters Patent, is—

1. The curved shuttle-carrier E' , the curved race B' , and the flanges d' , and pips g , in combination with the forked arm E^4 and means, 115 substantially as described, for rotary reciprocating the plate for reciprocating the carrier, substantially as described.

2. The curved shuttle-race B' , formed with a groove, d , and overhanging flanges d' , in 120 combination with the curved shuttle-carrier E' , having the flanges or projections d' , substantially as and for the purposes set forth.

3. The shuttle-carrier E' , provided with the pins g , in combination with the shuttle-race 125 B' , forked arm E^4 , and means, substantially as described, for rotary reciprocating the said arm, substantially as and for the purposes set forth.

4. The knives $S S'$, formed with cutting-fingers and held together by the spring U , in combination with the chains $W^2 W^3$, levers 130

W', and cam W, substantially as described.

5. The comb R and the sliding bars R', in combination with means, substantially as described, for reciprocating the bars horizontally,

5 and means, substantially as described, for tilting the comb upon its pivot, substantially as and for the purposes described.

6. The comb R and the sliding bars R', in combination with the cams R², levers R⁴, and springs R⁵, for reciprocating the comb, and

the cams R⁶, levers R⁷, and rods R⁸, arranged for tilting the comb, substantially as described.
